PERMANENT MOLD MACHINE FOR MAKING
TAPPETS

Joseph L. Dostal, Birmingham, Mich., assignor,
by mesne assignments, to Eaton Manufacturing
Company, Cleveland, Ohio, a corporation of
Ohio

Application July 29, 1935, Serial No. 33,717

3 Claims. (Cl. 22—77)

This invention relates to permanent molding machines and more especially to the type of machine comprising a conveyor which carries a plurality of pairs of cooperating mold sections, which sections, when brought together, provide mold cavities in which metal articles may be cast.

The principal object of the invention is to improve the art of producing cast iron articles having a hard and wear resistant surface over at least certain portions of such articles.

A further object is to provide apparatus for producing a one-piece hollow cast iron tappet so accurately to size as to minimize the amount of finishing operations required.

15 A further object of the invention is to so cast a hollow, one-piece tappet, closed at both ends, that one end, the cam engaging portion, will be chilled to produce a hardness so as to afford the desired wear resistance, Rockwell scale C, and the periphery will be chilled through to the core so as to have a slightly lesser hardness, and that the opposite end of the tappet will be correspondingly softer and readily machinable so that it may be readily bored and threaded to receive an adjusting element.

20 Another object is to produce a tappet having a hard cam engaging and peripheral surface and a correspondingly softer end portion banded by harder metal having higher tensile strength than said soft machinable portion so as to prevent distortion and expansion of the adjustment end of the tappet as a nut for the adjusting screw is tightened down against the tappet top.

25 A further object is to provide a cast tappet free from burned sand, particularly in openings or windows formed in the peripheral walls for the purpose of lightening the tappet.

It is also an object of the invention to provide a novel method of forming tappet windows of the 30 type disclosed in my co-pending application Serial No. 33,719, filed July 29, 1935.

Still another object of the invention is to provide a novel type of mold adapted to employ a core cover of sand or other refractory material for the 35 purpose of producing relatively soft and machinable top portion of a tappet.

Another object is to provide a novel means and method of locating and centralizing a core for 40 forming the interior cavity of a hollow, barrel type tappet.

It is also an object of the invention to make provision for venting gases from the mold of the 45 above type.

50 A further object is to provide a separate and

cooled section of a mold for forming the cam engaging portion of a tappet.

A further object of the invention is to provide a sectional type mold constructed and arranged so as to have a cooling medium circulated through 5 parts thereof.

Other objects, features and advantages will become apparent from the following description and appended claims.

For the purpose of illustrating the genus of the 10 invention, typical concrete embodiments are shown in the accompanying drawings, in which:

Figure 1 is a top plan of a permanent molding machine adapted for casting a barrel type tappet in accordance with the principles of this invention; 15

Fig. 2 is an enlarged, fragmentary section taken in a vertical plane substantially on the line 2—2 of Fig. 1;

Fig. 3 is a fragmentary top plan, similar to Fig. 1, but on an enlarged scale, of a modified form of permanent molding machine constructed according to the principles of this invention;

Fig. 4 is a vertical section, on an enlarged scale, taken substantially on the line 4—4 of Fig. 3;

Fig. 5 is a central vertical section taken through one of the molds and on a radial plane through the axis of either of the molding machines shown in Figs. 1 and 3;

Fig. 6 is a substantially vertical, central section 30 through a barrel type tappet, such section being taken approximately as indicated by the line 6—6 of this figure;

Fig. 7 is a fragmentary, central vertical section of a modified form of mold adapted to be employed in casting an open top type of barrel tappet; and

Fig. 8 is a section taken on the line 8—8 of Fig. 7.

In carrying out the present invention, there 40 may be provided an endless carrier, preferably in the form of a rotatable table 10, illustrated in Figs. 1 and 2 as carrying a plurality of molds 12. The table 10 may be formed by securing to a horizontally arranged disc-like part 14, provided with 45 a center hub 15 and a downwardly extending guide flange 16 at its periphery, a plurality of partial sectors 17, the latter together forming a circular ring extended outwardly from part 14. A plurality of partial sectors 20, each provided 50 with an upstanding flange 21 slightly spaced from the outer periphery thereof, are secured to each of the partial sectors 17 to form a further circular ring extended outwardly from the ring formed by the partial sector 17. Bolts 18 may be em- 55

ployed for securing the partial sectors 17 and 20 together and to the dislike part 14. A flange 21 is spaced from the periphery of the ring formed by the partial sectors 20 a sufficient distance to provide a ledge 22 of a width equal to one-half of the width in a radial direction of the molds 12.

The rotatable table 10 is journaled through the hub 15 and a bushing 23 therein for rotation with respect to a shaft 24. The lower end of shaft 24 is supported at the center of a circular support plate 25 adapted to be mounted in stationary condition to a suitable base or support, not shown. The outer portion of the stationary support plate 25 is offset upwardly to provide an upstanding shoulder portion 26 terminating in an annular guide rib 27 adapted to be received in an annular channel 28 provided in the guide flange 16 of the rotatable dislike part 14. Inwardly, but adjacent the upstanding shoulder 26, the stationary 15 or bed plate 25 is provided with a ledge 30 affording a horizontal bearing surface for a bearing 31 upon which a gear 32, fixed to the flange 16 of rotatable dislike part 14, is adapted to rotate.

The gear 32 is provided with internally directed 20 teeth 33 cooperable with a pinion 34 integral with or fixed to a pinion shaft 35 for the purpose of rotating the gear 32 to effect rotation of table 10. A gear mounting sleeve 36 is fixed to the shaft 35 and carries a bevel gear 37 adapted to be 25 driven by a pinion 43 fixed to or integral with shaft 42. The gear casing 40 is provided for supporting bearings 38 for the gear mounting sleeve 36 and shaft 35 and bearing 41 for the pinion shaft 42. A coupling 44 connects the drive 30 shaft 45 to pinion shaft 42 so that the rotatable table 10 may be operated from any suitable source of power, not shown, connected to the drive shaft 45.

A dislike air shield 50 provided with a suitable 40 central aperture 51 is supported from the upstanding flanges 21 of partial sectors 20. An upstanding collar 52 is provided at the margins of the central aperture 51 and encloses the lower end of a suction conduit 53 leading to an exhaust fan, not shown. The space between the elements 45 14, 17, and 20 and the air shield 50 constitutes a suction passage or chamber operating in conjunction with the suction conduit 53 and the exhaust fan associated therewith for drawing cooling air through the molds 12 and parts adjacent thereto. Openings 55 extend downwardly through the partial sectors 20 to the interior of a trough-like partial annulus 56 having openings 57 at the bottom thereof for each of a plurality of headers 50 60 secured thereto by means of bolts 61. The headers 60 are each provided with a lug 62 cooperable with ears 63 formed on swingable mold carriers 64, a pivot pin 65 connecting the ears of each of the swingable mold carriers to the lugs 62 65 of headers 60. The swingable mold carriers 64 are each provided with a passage 66 therethrough terminating in a curved conduit 67 having the axis of pivot pin 65 as a center and projecting through an opening 68 of header 60 so as to maintain communication at all times between the passages 66 of the swingable mold carriers and the interiors of the headers 60. A support 70, substantially of U-section, as viewed in Fig. 2, is fixed to the plate 25 and has bolted thereto a plurality 70 of brackets 71, one bracket being individual to each of the swingable mold carriers 64. To the upper end of each of the brackets 71 is pivotally connected a bell crank lever 72 provided with a journaled roller 73 engageable with a cam contact 74 provided on each of the swingable mold

carriers 64. Springs 75 extending between an arm 76 provided on each of the brackets 71 and an arm of bell crank levers 72 normally bias the rollers 73 into engagement with the outer marginal surfaces of the cam contacts 74.

The swingable mold carriers 64, in practice, swing about the pivot 65 outwardly through an angle of approximately 30 degrees when not engaged by the roller 73 or other operating means therefor. Rotation of the table 10 in a clockwise direction as viewed in Fig. 1, causes the cam contact 74 of each of the swingable mold carriers 64 to successively engage a cam 76 so as to swing the mold carriers 64 inwardly toward the shaft 24 and to close the mold sections and permit the rollers 73 of bell crank lever 72 and spring 75 yieldingly to maintain the mold sections in closed condition. The cam contacts 74 are provided with a beveled inner surface 77 engageable with a cam 78 beyond the series of rollers 73 so that a downwardly projecting lip on cam 78 will cause opening of the molds as the cam 78 causes outward swinging of the mold carriers 64 as indicated in Fig. 1. The cams 76 and 78 are carried by the support member 70.

Referring to Figs. 2, 5, and 6, the molds 12 are illustrated as comprising sections 80 and 81 separable with reference to a vertical parting line 82. The main mold sections 80 and 81 are each provided with a semi-cylindrical mold cavity 83 so that the two cavities form a cylindrical bore extending vertically and longitudinally through each of the separable molds 12. A separate mold section 84 substantially in the form of a hollow piston, closed at the upper end 85 and provided with a cooling fin 86 so that the separate section forms the lower end of the tappet 95, is depicted in Fig. 5. A pin 87 extending from the stationary main mold section 81 may project through an opening 88 to determine the elevation of the separate section 84. A plurality of such openings 88 may be provided cooperable with the pin 87 so as to obtain slight variations in the lengths of the tappets produced. The separate section 84, which forms the bottom of the tappet 95, is hollow to form an air passage for the circulation of cooling air therethrough and, accordingly, its length is made several times its diameter in order effectively to cool the same than to attain the desired chill of the cam engaging end of the tappet 95. A permanent mold comprising two main sections separable along a vertical parting line and provided with impressions 83, enables the production of tappets very close to the finished diameter desired so as to eliminate as much 55 grinding as possible on the outside surface of the tappet. The impression 83 in each of the mold sections 80 and 81 has projections 90 which form openings in the hollow tappet 95 of the desired size and shape and extend to the walls of such 60 hollow tappets so as to communicate with a dry sand core 93 which forms the hollow interior of the tappet, thereby locating the core in diametrically correct position. A locating pin 94 may be provided in one of said projections for holding 65 the core in the correct vertical position, opening 96 being provided in the core in a predetermined position to secure the correct vertical elevation of the core desired.

A permanent mold corrects several difficulties 70 normally encountered in producing tappets in the ordinary sand mold. It is extremely difficult to produce castings by the sand method in order to obtain close tolerances and eliminate much of the grinding required for finishing the outside 75

surface of the tappets. It is also difficult in casting by the sand method to obtain clean castings free from burned-in sand, especially in the openings or windows 92 cast in the periphery of the tappet for the purpose of lightening the same. This burned-in sand is very difficult and expensive to remove and undesirable in an internal combustion engine since the sand frequently loosens and causes scoring of the tappet or tappet guide as well as getting into the lubricating system of the motor so as to endanger bearings or other moving parts of an internal combustion engine.

In making the tappet 95 by the permanent mold method, the latter condition is entirely eliminated in the windows 92 of tappet 95, as such windows are formed by the integral projections 90 in the permanent mold sections 80 and 81, and due to the rapid chilling effect of the metal mold sections, the sand of the core 93 does not have a chance to burn in or on parts of the cast tappet.

Another disadvantage of the tappet cast by the sand method is that it is impossible to obtain a hard peripheral surface and a soft top which is machinable so that it may be bored and threaded as indicated at 97 in Fig. 6 for the purpose of receiving an adjusting screw. With both the main mold sections 80 and 81 and the separate bottom section 84 of metal, both the cam engaging surface of tappet 95 and the entire periphery of the cylindrical body portion of the tappet will be of chilled metal entirely through the wall portions of the tappet to the interior of the tappet or to the core 93 as long as the mold sections 80, 81, and 84 are kept in a sufficiently cool condition.

A top of the tappet may be made softer and more machinable in order more readily to bore and to thread the screw holes 97 by providing complementary recesses 100 in the upper part of the two main sections 80 and 81, the recesses 100 being adapted to receive a cover core 101 of dry sand or other refractory material, for forming the top or adjustment end of the tappet 95. Due to the refractory nature of the material composing the cover core 101, the upper end of tappet 95 is not chilled at this point, but is kept in a soft and readily machinable condition. The cover core 101 is provided with a central aperture 102 which serves as a gate for filling the mold.

The following analysis of iron affords an example of a material suitable for producing an all chilled tappet, or one that has a cam engaging surface and outer periphery of the body chilled but whose top or adjusting screw end may be left soft for machining purposes, and may consist of: Carbon 2.75 to 3.50 per cent, silicon 1.70 to 2.60 per cent, phosphorus 0.20 to 0.30 per cent, manganese 0.40 to 1.10 per cent, sulphur 0.115 per cent, and the balance iron.

A pair of pouring blocks 103 and 104 separable along the parting line 82 constitute a two-piece pouring basin at the top of the mold and are provided with cooperable recesses forming a gate 105 registerable with the opening 102 of cover core 101 so that the two-piece pouring basin may serve as a sprue and gate for pouring the casting. The mold surfaces of the main mold sections 80 and 81 preferably treated with a refractory facing and sooted in the manner disclosed in Maloche Patents 1,453,593 and 1,492,694. The top of the cover core 101 is arranged substantially flush with the top surfaces of the main mold sections 80 and 81, except for radially disposed vent grooves 106 cut to a depth of approximately 0.015

of an inch for the purpose of providing passages for venting gases from the interior of the mold. The backs of the pouring blocks 103 and 104 are hollowed out as indicated at 107 and 108 and communicate with hollowed out portions 109 and 110 in the backs of the main mold sections 80 and 81 so that cooling air may be circulated about the mold 12 to maintain the desired temperature condition thereof and obtain the desired hardness of the tappet produced.

The main mold section 81 is provided with a passage 112 registerable with a passage 114 through the wall of the separate section 84 so that cooling air may be drawn in from the bottom of the pistonlike separate section 84, around 15 the cooling fin 86, through the passages 114 and 112 to the hollowed out space 110 in the back of main mold section 81, and thence through an opening 115 provided adjacent the bottom of the upstanding flange 21 of the partial sector 20 20 which serves as the stationary carrier for main mold section 81 of mold 12. The upstanding flange 21 of the stationary mold carrier 20 is provided with an air passage 116 registerable with the hollowed out portion 108 of pouring block 104 25 and another passage 117 registerable with the upper portion of the hollowed out chamber 110 of mold section 81 so that cooling air may be drawn into the passages 116 and 117 through the hollowed out portions 108 and 110, and thence 30 through the passage 115 to the suction chamber 54 adapted to be exhausted by the suction fan associated with the conduit 53. It is noted that air will take this course irrespective of whether the mold sections are in open or closed condition. 35 The swingable mold carrier 64 is provided with an upstanding flange 121 corresponding to the flange 21 of the stationary mold carrier 20 and is provided with passages 122 and 123 therethrough, through which passages air may be drawn into 40 the hollowed out portions 107 and 109 of main mold section 80 and thence through the passage 66 and curved conduit 67 of the swingable mold section 64 to the interior of header 60, thence through the interior of the supporting element 56 45 to the suction chamber 54. It is also noted that air is drawn through this core at all times whether the swingable mold carrier 64 is in open or closed position.

While cooling of the mold could be effected by 50 circulating air or other cooling medium in the reverse direction from that described, in the case of air it is preferred to circulate it in the described direction since this does not cause excessive amounts of heat to be given off from 55 the molding machine and thus, does not make working conditions disagreeable or even unbearable for attendants of the machine.

Reference may now be had to Figs. 3 and 4, which disclose a slightly different form of molding machine provided with a rotatable conveyor 10' adapted to carry a series of molds 12' in much the same manner as described relative to the previous embodiment. The conveyor 10' supports stationary mold carriers 21' and swingable mold carriers 64' of essentially the same construction as previously described. The headers 60' of the present embodiment, however, each carry an adjustable support for the pivot 65' of 60 the swingable mold carrier 64' which is adapted to be secured in adjusted position by means of the bolts 125. The pivot support 124 is also provided with a guide member 126 having a forked upper end 127 adapted to guide and brace, as 70 75

well as limit the outward swinging movement of, the movable mold carriers 64'.

In the embodiments shown in Figs. 3 and 4 the rollers 73' are adapted to engage the outer periphery of cam contacts 74' for the purpose of maintaining the mold 12' in closed condition, as before. The rollers 73' are mounted in slide members 12' arranged for reciprocation in recesses 130 provided in holders 131 and springs 10 75' are interposed within suitable bores within the slide members 12' so that the swingable members 64' are maintained in closed condition under spring pressure. The spring pressure for maintaining the swingable mold carriers 64', 15 however, does not exert a lateral thrust upon the shaft 24'. A support member 132 includes a bearing 133 within which the shaft 24' is journaled, a pair of radially extending arms 134 and a bridge member 135 upon which the support 20 blocks 131 are mounted by means of bolts 136. The bolts 125 and 136 both pass through enlarged openings or slots in the header member 60' and bridge member 135 so that the pivot of the swingable mold carrier 64' may be adjusted 25 and thus permit proper alignment of the mold sections when the molds are in closed condition and also permit adjustment of the mounting blocks 131 so that the tension of springs 75' may be adjusted to vary the spring pressure exerted 30 for maintaining the molds in closed condition. A roller carrier 137 is bolted to the outer ends of the arms 134 and pivotally supports a plurality of rollers 138 arranged in a circular series with the axis of shaft 24' as a center. The rollers 35 138 bear upon the backs of the flanges 21' of the stationary mold carriers 20' so as to relieve the shaft 24' of lateral pressure exerted by the springs 75' in maintaining the molds 12' in closed condition. Cams 76' and 78' serve to open and 40 to close the molds 12' as before. The construction of the molds 12' and the construction and arrangement of the cooling system for the molds and associated parts is essentially the same as that described relative to the embodiment shown 45 in Figs. 1, 2, and 5.

Reference may now be had to Figs. 7 and 8, which disclose a modified form of mold adapted to cast an open top type of tappet 95'. In this mold construction, the main mold sections 80' and 81' are not recessed adjacent the top thereof and no cover core corresponding to the core 101 of Fig. 5 is employed. Pouring blocks 103 and 104 providing a central gate 105 are employed as in the previously described embodiment. The 50 core 93', in the present instance, extends upwardly to a point closely adjacent the bottom surface of the pouring blocks 103 and 104 and is enlarged and axially grooved in its periphery adjacent the upper end thereof so that plurality 55 of pouring sprues 140, four of such sprues being indicated in Figs. 7 and 8, are formed during the casting of the tappet 95'. Windows are formed in the side walls of the tappet 95' in much the same manner as depicted in Figs. 5 and 6. A separate section 84' is provided for forming the cam engaging portion of the tappet 95'. The main sections 80' and 81' and the separate section 84' are cooled to the desired 60 temperatures as before so as to chill the cam engaging and peripheral portion of the tappet to obtain the desired hardness and wearing qualities of the tappet formed.

As many changes could be made in the above

described constructions, and many apparently widely different embodiments of this invention could be had without departing from the spirit thereof, it is intended that all matter contained in the above description or shown in the accompanying drawings shall be interpreted as illustrative, and not in a limiting sense. 5

What is claimed is:

1. A casting machine comprising, in combination, a movable carrier, a mold including two main sections parted vertically, each section having a mold impression cooperable with the impression of the other section for forming a mold cavity and a separate section forming the bottom wall of such mold cavity, a dry sand core within the mold cavity, a cover core, said main mold sections each being provided with a recess for receiving a portion of said cover core, and means for circulating a cooling medium through said carrier and through each of the mold sections, said cover core being constructed of refractory material to shape one end of the casting formed but to prevent chilling of the casting at this point so as to maintain such end of the casting in a soft and machinable condition. 15

2. A casting machine comprising, in combination, a movable carrier, a mold including two main sections parted vertically, each section having a mold impression cooperable with the impression of the other section for forming a mold cavity and a separate section forming the bottom wall of such mold cavity, said main mold sections each being provided with a recess adjacent the upper end thereof, a core composed of refractory material arranged within the mold cavity, a cover core of refractory material arranged within the recesses of said main section and adapted to shape one end of the casting formed but to prevent chilling of such end of the casting so as to maintain the same in a soft and machinable condition, and means for circulating a cooling medium through said carrier and through each of said mold sections, said cover core being provided with a central opening therethrough so as to form a gate for filling the 40 mold cavity. 30

3. A casting machine comprising, in combination, a movable carrier, a mold including two main sections parted vertically, each section having a mold impression cooperable with the impression of the other section for forming a mold cavity and a separate section forming the bottom wall of such mold cavity, said main mold sections each being provided with a recess adjacent the upper end thereof, a core composed of refractory material arranged within the mold cavity, a cover core of refractory material arranged within the recesses of said main section and adapted to shape one end of the casting formed but to prevent chilling of such end of the casting so as to maintain the same in a soft and machinable condition, and means for circulating a cooling medium through said carrier and through each of said mold sections, said cover core being provided with a central opening therethrough so as to form a gate for filling the 50 mold cavity, the upper surface of said cover core being arranged flush with the upper surface of said main mold section and said main mold sections each being provided with a groove in the 55 upper surface thereof for venting gases from the upper surface thereof for venting gases from the 60 mold cavity. 65

JOSEPH L. DOSTAL.
